UNITED STATES PATENT OFFICE.

STONE E. EKLUND, OF TOLEDO, OHIO.

SCALE.

1,077,265.

Specification of Letters Patent.

Patented Nov. 4, 1913.

Application filed February 26, 1912. Serial No. 680,076.

To all whom it may concern:

Be it known that I, STONE E. EKLUND, a citizen of the United States, and a resident of Toledo, in the county of Lucas and State of Ohio, have invented a certain new and useful Scale; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

My invention relates to scales, and particularly to counter or similar scales, but is not restricted to such use, as it may be used in any connection for which it is adapted. In scales of this class it has been customary to provide the scale-levers thereof with two weights, namely, a major weight, which is usually fixed to the short arm of the lever, and a pendulum weight, which is usually attached, through a cam and ribbon connection, to the opposite end of the lever from that carrying the major weight, and which normally hangs in neutral position, or about 7° from neutral position. Considerable experimenting has been done by scale builders in an endeavor to eliminate the necessity of using such major weight, as its presence on the scale-lever is objectionable due to the wear and friction occasioned thereby on the fulcrum points of the lever, and also to the clumsy and heavy appearance which the presence of a large weight (usually an eighteen pound weight for a twenty-four pound scale) gives to the scale.

The object of my invention is to overcome and eliminate such objectionable features from scales of this character, and also to simplify, lighten and cheapen the construction thereof, whereby to enhance the practicability and commercial value of such scales.

A further object of my invention is to overcome an inaccuracy which is found to be present in scales of this character, as hereinafter more fully described.

The invention is fully described in the following specification, and while, in its broader aspect, it is capable of embodiment in numerous forms, a preferred embodiment

thereof is illustrated in the accompanying drawings, in which—

Figure 1 is a rear elevation of a scale embodying my invention. Fig. 2 is a side elevation thereof, and Fig. 3 is a plan of the scale-lever employed.

Referring to the drawings, 1 designates the base of a scale; 2 the hollow pendulum-housing, or standard, which rises from the forward end portion of the base and supports the housing 3 in which the computing cylinder 4 is mounted, 5 the scale-lever, 6 the platter, which is carried by the lever, and 7 a forked bearing standard, which rises from the rear end portion of the base and carries the scale-lever, all of which parts are common in one form or another in scales of this character.

The scale-lever 5 is shown, in the present instance, as having its major or body portion of rectangular frame form, see Fig. 3, and provided with the customary knife-edge fulcrum-studs 8 projecting from opposite sides thereof adjacent to its rear end for bearing on the respective arms of the standard 7, and is provided in advance of such studs with similar knife-edge studs 9 upon which the platter-supporting frame 10 has its bearings, as well understood in the art.

The forward end of the lever body has an arm 5^a projecting forwardly therefrom, within the hollow of the standard 2, and attached, through the medium of a connecting loop 11 and metal ribbon 12, with the cam 13 at the upper end of the pendulum 14, in the usual manner, to cause a lowering of the forward end of the scale-lever to effect a raising of the lower weighted end of the pendulum in an arc of a circle from its normal position, as well understood in the art. The pendulum has knife-edge pivot-studs 15 mounted in suitable bearings 16 within the standard. The lever 5 is also shown as having an arm 5^b projecting therefrom for attaching to the rack-bar 17 customarily employed for coöperating with a pinion 18 on the computing cylinder shaft to communicate rotation to such cylinder from a movement of the scale-lever, if such cylinder is used.

In carrying out the feature comprising my invention, I eliminate the weight, which it has heretofore been the practice to attach to the rear end or short arm of the scale-

lever, and in lieu thereof adjust the pendulum 14 relative to the scale-lever so that it will preferably normally hang approximately 40° off the vertical plane with its axis, 5 as shown in Fig. 1, instead of 0° , or between 0° and 7° , as has heretofore been the case. The pendulum 14 normally stands in the initial inclined position shown in the figures by reason of its being in equilibrium with the 10 scale beam and other poising elements when in such position. With this arrangement, the objectionable major weight of the scale-lever is not only rendered unnecessary but it is found in practice that the inaccuracies 15 in weighing, which are present with the old form of scale referred to, are entirely overcome. This adjustment of the pendulum also causes a sufficient weight or pull upon the ribbon 12 under normal conditions, or 20 when the pendulum is at its lowered at-rest position, so as to maintain such ribbon taut at all times, whereas with the old adjustment thereof an insufficient pull was exerted upon the ribbon 12 to prevent the presence 25 of loops of slackness therein, thus in the latter case contributing largely to the inaccuracies present in scales of this character.

While I have shown and described my invention in association with a particular type 30 and construction of scale, it is to be understood that its scope is not so limited, and that it is intended for use in any connection for which it may be adapted or appropriate.

35 Having thus described my invention, what I claim as new, and desire to secure by Letters Patent, is,

1. In a scale of the character described, a scale lever carrying an article supporting

means fulcrumed adjacent one end in a fixed 40 support, a pendulum weight also fulcrumed in a fixed support having a cam projection and a ribbon connecting the same with the free end of the vertical lever, said fulcrum weight being held in poise at an inclination 45 to a vertical plane in the normal zero position of the parts by the weight of said scale lever and the article supporting means and serving the double purpose of a counterpoise for said parts and as a counterweight 50 for articles to be weighed.

2. In a scale, the combination of a base, a rigid bearing affixed to one end of said base and having a forked upper end, a hollow casing secured to the other end of the base, 55 a pendulum weight fulcrumed in said casing, a cam carried by said pendulum weight, a scale lever comprising an open rectangular frame from opposite sides of which project knife-edge studs supported on the 60 forked upper end of the rigid bearing, an arm projecting from said lever into said casing, a ribbon or like flexible connection between said arm and the cam carried by the pendulum lever, a second pair of knife-edge 65 studs projecting from the lever frame parallel to the first-named studs, an article supporting platform carried by said second mentioned knife-edge studs, arms projecting outwardly from said lever frame and a tare 70 beam connected to said arms.

In testimony whereof, I have hereunto signed my name to this specification in the presence of two subscribing witnesses.

STONE E. EKLUND.
